UNITED STATES PATENT OFFICE

GLADEON M. BARNES, OF THE UNITED STATES ARMY, HASTINGS, MICHIGAN

GUN

Application filed December 10, 1930. Serial No. 501,325.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

This invention relates to guns and, more particularly, it has reference to that class of guns wherein a portion of the powder gases of discharge are utilized for retarding the recoil movement of the gun, being compressed in this operation and made available for restoring the gun to battery.

The gun forming the subject matter of the present invention is characterized by the association of a novel type of muzzle brake with a cylinder for collecting the deflected gases for compressive action and reaction.

To these and other ends, the invention consists in the construction, arrangement and combination of elements described hereinafter and pointed out in the claims forming a part of this specification.

A practical embodiment of the invention is illustrated in the accompanying drawing, wherein:

Fig. 1 is a more or less diagrammatic illustration in the nature of a longitudinal sectional view through a gun exemplifying the principles of the invention;

Fig. 2 is a sectional view on the line 2—2 of Fig. 1; and

Fig. 3 is a longitudinal sectional view showing a modified arrangement of the inlet valve.

Referring to the drawing by characters of reference:

There is shown a gun 5 of the reciprocating type arranged to slide in a cradle, a portion of which is indicated at 6. A cylinder 7 forwardly connected to the gun by means of a hanger 8 is also secured to the gun lug 9 through its rear head 10 and the nut 11 so that it partakes of the movement of the gun.

An imperforate casing 12 mounted on the muzzle of the gun and secured thereto in any convenient manner, specifically by a pin 13,

is in communication through a pipe 14 with a passage 15 in a valve block formed by the hanger 8. This passage leads to a valve chamber 16 which in turn is open to a port 17 in the cylinder. A valve 18 in the chamber 16 is normally held in the open position by its spring 19, being limited in movement by the engagement with the valve block of a nut 20 on the outer end of the valve stem.

Within the casing 12 there are a series of baffle rings 21 centered by means of laterally projecting lugs 22 and held in spaced relation with respect to each other by axially projecting lugs 23. The innermost ring 21a is specially shaped to abut the end of the gun and the outermost ring 21b is imperforate and threaded to the casing to secure the remaining rings in place. The rings 21 are triangular in cross-section and formed with a concave base 24 so that when arranged with the base directed to the gases of discharge issuing from the gun, they will serve to deflect the gases rearwardly for delivery to the cylinder 7.

A piston 25 held stationary by virtue of attachment to the cradle 6 works in the cylinder 7 and has its head 25a normally positioned at the rear of the cylinder when the gun is in battery. A passage 26 in the piston head is controlled by a valve 27 to regulate the volume of gas permitted to pass from the compression chamber 28 to the low pressure side of the piston where a buffer chamber 29 is established. The buffer chamber is provided with a relief valve 30.

In the arrangement shown in Fig. 3 the valve 31, corresponding to the valve 18 of Fig. 1, has been reversed to position the valve stem 32 and the spring 33 outside of the valve block so that they will not be in contact with the hot powder gases passing through the valve chamber.

In operation, when the gun is fired, the gases of discharge enter the casing 12, expand rapidly and are deflected to the rear by the baffle rings 21. The action in checking

the energy of recoil of the gun is the same as obtains in the conventional muzzle brakes. However, the deflected gases, instead of being vented directly to atmosphere where they 5 interfere with the gun crew and give rise to clouds of dust, are delivered to the cylinder 7, entering past the normally open valve 18.

During the initial stage of recoil the pressure in the cylinder exceeds the rapidly decreasing pressure in the casing 12 and effects 10 the closing of the valve. Thereafter the gases confined in the cylinder will be compressed as the forward end of the cylinder approaches 15 the stationary piston head 25a, acting to yieldingly check the recoil of the gun and reacting to return the gun into battery. A portion of the gases permitted to enter the buffer chamber 29 through the valve passage 26 will be compressed on the counterrecoil 20 stroke thereby easing the gun into battery. The cylinder is relieved through the valves 18 and 30.

It is to be understood that in a gun employing an evanescent medium in the recoil 25 and counterrecoil mechanism, some provision is to be made for holding the gun in battery.

I claim:

1. In a reciprocating gun, a cylinder movable with the gun, a stationary piston in the cylinder, a valve block on the cylinder, a chamber in the block having communication with the cylinder, a normally open valve in the chamber, and a muzzle brake on the gun delivering gases of discharge to the chamber 30 in the valve block.

2. In a reciprocating gun, a recoil mechanism utilizing the gases of discharge to check recoil and restore the gun to battery, a muzzle brake on the gun having a series of baffle 35 rings arranged to deliver gases of discharge to the recoil mechanism, and a normally open valve in the path of delivery closed by pressure in the recoil mechanism.

3. In a reciprocating gun, a recoil mechanism utilizing the gases of discharge to check recoil and restore the gun to battery, a muzzle brake on the gun arranged to deliver gases of discharge to the recoil mechanism, and a normally 40 open valve in the path of delivery closed by pressure in the recoil mechanism.

4. In a reciprocating gun, a recoil mechanism utilizing the gases of discharge to check recoil and restore the gun to battery, and a muzzle brake on the gun having a series of baffle 45 rings arranged to deliver gases of discharge to the recoil mechanism.

5. In a reciprocating gun, an imperforate casing secured to the muzzle of the gun and

having a rearwardly directed passage, a series of baffle rings in the casing, said rings being triangular in cross section with a concave base, laterally projecting lugs on the rings engaging the casing, axially projecting lugs on the rings engaging an adjoining ring, 50 and means for collecting gases of discharge, 55

deflected by the baffle rings and delivered through the passage.

6. In a reciprocating gun, an imperforate casing secured to the muzzle of the gun and having a rearwardly directed passage, baffling means in the casing for reversing the direction of the gases of discharge, a receptacle for collecting the gases of discharge and means for delivering the collected gases to a movable part of the gun.

GLADEON M. BARNES.
